DISPLAY CABINET

Roger A. Schindler, Hampton Township, Allegheny County, Pa., assignor to Flannery and Associates, Inc., Springdale Township, Allegheny County, Pa., a corporation of Pennsylvania

Filed Feb. 15, 1963, Ser. No. 73,583

Term of patent 14 years

(Cl. D80—11)

Fig.1.

Fig.2.

Fig.3.

Fig.4.

Fig. 5.

Fig. 6.

FIGURE 4 is a front perspective view similar to FIGURE 3 but with said lower portion in a partially closed position;

The rear of the display cabinet is identical with the front.

I claim:

The ornamental design for a display cabinet, as shown and described.
